UNITED STATES PATENT OFFICE.

THOMAS C. LEAKE, OF SAN FRANCISCO, CALIFORNIA, ASSIGNOR TO LEAKE MOTOR FUEL ECONOMY COMPANY, A CORPORATION OF CALIFORNIA.

HEATER AND THERMOSTAT ATTACHMENT FOR MOTORS.

1,137,219.

Specification of Letters Patent. Patented Apr. 27, 1915.

Application filed April 9, 1914. Serial No. 830,709.

To all whom it may concern:

Be it known that I, THOMAS C. LEAKE, a citizen of the United States, residing in the city and county of San Francisco and State of California, have invented new and useful Improvements in Heaters and Thermostat Attachments for Motors, of which the following is a specification.

The invention relates to internal combustion engines and particularly to a means for feeding fuel thereto.

It is very desirable to employ comparatively heavy hydrocarbons, such as distillate, as the fuel in internal combustion engines, owing to its low cost in comparison with the cost of the lighter hydrocarbons such as gasolene, but great difficulty has been heretofore experienced in starting the cold engine on distillate.

It is one of the objects of my invention to provide a fuel feeding means whereby the engine, even when cold, may be started on distillate as a fuel.

A further object of the invention is to provide means for feeding distillate directly to the cylinders when the engine is cold and for automatically cutting off this feed and supplying the fuel in the usual way, by means of a carbureter, when the engine becomes warm.

The invention possesses other advantageous features, some of which, with the foregoing, will be set forth at length in the following description where I shall outline in full that form of the invention which I have selected for illustration in the drawings accompanying and forming part of the present specification. In said drawings, I have shown only one form of my invention but it is to be understood that the invention may be embodied in other forms without departing from the spirit of my invention. It is also to be understood that, by the claims succeeding the description of the invention, I desire to cover the invention in whatever form it may be embodied.

In said drawings: Figure 1 is an elevation of an internal combustion engine showing the apparatus of my invention attached thereto. Fig. 2 is a longitudinal section of the thermostatic means for controlling the flow of fuel. Fig. 3 is a section of the controlling valve, taken on the line $x-x$ Fig. 2. Fig. 4 is a longitudinal section of the fuel heater taken on the line $y-y$ Fig. 5.

Fig. 5 is a cross section of the fuel heater taken on the line $z-z$ Fig. 4. Fig. 6 is a view of the under side of the pipe 18 on a larger scale, showing the vent hole.

As shown in the drawings, A represents the cylinders of an engine, 2 the manifold, and 3 the carbureter supplying the mixture to the engine chamber.

4 is a suitable container for the hydrocarbon to be used, which hydrocarbon is led by 5 to the heater. This heater is represented by a casing 6, through which an exhaust pipe 7 passes, and the pipe 5 forms a coil 8 of as many turns as may be found desirable, which coil passes around in the casing 6 and has its exit through a pipe 9. When the engine starts, the exhaust pipe becomes heated, and the temperature of the distillate is raised to such a point that it is readily vaporized in the carbureter. The carbureter is of the usual construction, being provided with a float and float chamber, whereby the level of the distillate at the hydrocarbon nozzle is maintained substantially constant. The manifold is provided with a throttle valve immediately above the carbureter, which is controlled by the rod 19.

Means are provided for introducing the unvaporized distillate into the upper part of the manifold before the distillate becomes sufficiently warm to be vaporized by the carbureter and for shutting off this supply direct to the manifold as soon as the distillate becomes sufficiently warm. By introducing the cold distillate into the upper portion of the manifold, it is readily drawn into the cylinders where it explodes, whereas, in its cold condition, it cannot be raised through the manifold from the carbureter. The distillate is conveyed into the carbureter through the pipe 11 and between pipe 9 and pipe 11 is a hollow casing 10 through which the distillate passes. The casing 10 is provided intermediate its end with an outlet 12, which is connected to the manifold by the pipe 18. This pipe extends upward in a loop above the level of tank 4, so that when the engine is cold and at a standstill, the distillate will not continually flow into the manifold. At the upper or looped part of pipe 18 I provide a very small vent hole 21 which admits air to the pipe very slowly, so that, with the outlet 12 open and the engine stopped, the distillate will not siphon into the manifold. The air vent also

105
110

allows the distillate on the discharge side of pipe 18 to slowly pass into the manifold when the outlet 12 has been closed, but the size of the vent is such that it does not prevent the distillate being drawn into the manifold when the engine is being turned over or is turning over, and the outlet 12 is open, and does not allow distillate to discharge through the aperture.

10 Thermostatic means are employed for closing the outlet 12 when the temperature of the distillate reaches the required degree. Arranged over the outlet 12 is a ball valve 13 connected to the rod 17 by means of the links 14, and means are employed for depressing the rod 17 and seating the ball when the temperature of the distillate in casing 10 has reached the required degree. This means consists of two rods 15, which 20 may be of zinc or other material which will expand to a greater extent than the outer casing in which they are contained. At the outer ends these rods are pivoted, as at 16, and at their inner ends they are pivoted together at their point of meeting, and a connecting-hod 17 depends from the joint so that the links 14 are connected with its lower end. The object of this construction is to provide for the opening and closing of 30 the valve 13 by the variation in temperature of the bars 15. An important point in this construction is in so constructing the hollow case 10 that the meeting point of the rods 15 is below their pivot point 16 at the outer end. It will be seen, therefore, that when the liquid enters this pipe, the temperature will control the movement of the rods 15 and the valve 13. Normally, the valve 13 will be open by reason of the construction of the rods 15 which lift it from its seat.

The operation of the apparatus is as follows: Assuming that the engine and the distillate are cold, and that the engine is at 45 standstill. In this condition the outlet 12 is open. As the engine is turned over, distillate is drawn through the pipe 18 into the upper end of the manifold and thence into the cylinders, where it ignites and starts the engine. This method of running is not economical and is advisable only at starting. When the engine operates, the exhaust pipe, and consequently the distillate flowing 55 through pipe 9 into the casing 10, becomes heated. When the temperature of the distillate in the casing becomes such that it may be properly volatilized by the carbureter, the outlet 12 is automatically closed and the fuel enters the cylinders entirely 60 through the carbureter.

Having thus described my invention, what I claim and desire to secure by Letters Patent is—

1. An attachment for an internal combustion engine having a manifold and carbureter, consisting of a hydrocarbon fuel supply pipe connected to the carbureter, a pipe connecting the fuel supply pipe with the manifold, means for heating the fuel, and means operated by the rise in temperature 70 of the fuel for cutting off the flow of fuel directed into the manifold.

2. An attachment for an internal combustion engine having a manifold and carbureter, consisting of a source of hydrocarbon supply, a pipe connecting said supply with the carbureter, a casing forming a part of said pipe, a pipe connecting the casing with the upper part of the manifold adapted to conduct hydrocarbon directly to the manifold, means for heating the hydrocarbon, and means operated by the rise in temperature of the hydrocarbon for cutting off the flow of hydrocarbon directed to the manifold.

3. An attachment for an internal combustion engine having a manifold, consisting of means for introducing liquid hydrocarbon directly into said manifold, means for heating the hydrocarbon before it enters the manifold, and means operated by a rise in temperature of the hydrocarbon for cutting off the direct supply thereof to the manifold.

4. An attachment for an internal combustion engine having a manifold and carbureter, consisting of a fuel supply tank, pipes connecting said tank with the carbureter and with the manifold, whereby fuel is fed to the carbureter and directly to the manifold and means for automatically controlling the supply of fuel directed to the manifold.

5. An attachment for an internal combustion engine provided with a manifold and carbureter and exhaust pipe, consisting of a fuel supply tank, a conductor extending from said tank to the carbureter disposed in thermal communication with the exhaust pipe, a casing interposed in said pipe, a pipe leading from said casing to the upper part of the manifold whereby fuel may be fed directly into the manifold, and thermally operated means in said casing for controlling the flow of fuel through said last mentioned pipe.

6. An attachment for an internal combustion engine provided with a manifold, carbureter and exhaust pipe, consisting of a fuel supply tank, pipes connecting said tank with the carbureter and with the manifold and disposed in thermal communication with the exhaust pipe, whereby the fuel is heated, and means for automatically controlling the flow of fuel directed to the manifold.

7. An attachment for an internal combustion engine provided with a manifold, carbureter and exhaust pipe, consisting of a fuel supply tank, a casing, a pipe extending from said tank to said casing and in ther-

mal communication with the exhaust pipe, a pipe connecting the casing with the carbureter, a third pipe connecting the casing with the upper part of the manifold, a valve 5 controlling the communication between the casing and said third pipe and a thermostat in said casing for controlling the position of said valve.

8. An attachment for an internal combustion engine provided with a manifold, carbureter and exhaust pipe, consisting of a 10 fuel supply tank, a fuel pipe connecting the tank with the carbureter and disposed in thermal communication with the exhaust

pipe, a pipe connecting said fuel pipe with the upper part of the manifold and extending above the level of the supply tank, and thermally operated means for controlling the flow of fluid through said last named pipe.

In testimony whereof I have hereunto set my hand in the presence of two subscribing witnesses.

THOMAS C. LEAKE.
